CURT KUENTZEL, OF AKRON, OHIO, ASSIGNOR TO THE GOODYEAR TIRE AND RUBBER COMPANY, OF AKRON, OHIO, A CORPORATION OF OHIO.

WRAPPING AND UNWRAPPING MACHINE.

1,101,555.

Specification of Letters Patent. Patented Jun 30, 1914.

Application filed May 12, 1913. Serial No. 767,058.

To all whom it may concern:

Be it known that I, CURT KUENTZEL, subject of William II, Emperor of Germany, residing at Akron, in the county of Summit 5 and State of Ohio, have invented new and useful Improvements in Wrapping and Unwrapping Machines, of which the following is a specification.

This invention relates to machines for 10 wrapping a strip of material on or unwrapping a strip of material from some object such as a continuous cable or wire or an annular article such as a tire or tire shoe.

The invention is especially adapted for 15 wrapping and unwrapping tires both before and after the vulcanizing process, for wrapping tires for shipment, also for covering and uncovering wire and cables with paper, tape, fabric, etc.

20 The invention contemplates the provision of a machine for unwrapping a strip of material from articles which permit the spooling up of a strip of material during the process to thereby permit the material to be 25 used again if desired on other goods, without a second operation being necessary for spooling.

The invention is for the same general purpose as the machine shown, described and 30 claimed in United States Letters Patent granted to me Nov. 25, 1913, No. 1,079,601, for a wrapping and unwrapping machine.

With the foregoing and other objects in view, the invention consists in the novel construction, combination and arrangement of parts constituting the invention to be herein-after specifically described and illustrated in the accompanying drawings which form a part hereof wherein is shown the preferred 40 embodiment of the invention, but it is to be understood that changes, variations and modifications can be resorted to which come within the scope of the claims hereunto appended.

45 In the drawings in which similar reference numerals indicate like parts in the different figures, Figure 1, is a view in front elevation of a machine embodying this invention; Fig. 2, is a view in side elevation 50 looking from the right in Fig. 1; Fig. 3, is an enlarged detail of the shuttle employed and shown in the operation of winding a strip of material on a tire; Fig. 4, is a view similar to Fig. 3 showing the shuttle in the 55 operation of unwinding a strip of mate-

rial from a tire; Fig. 5, is a view in side elevation of a bobbin carrier employed; Fig. 6, is a view in section of a portion of the mechanism shown in Fig. 5; and, Fig. 7, is an enlarged detail of a device for supporting 60 the upper portion of a tire while within the machine.

For convenience of description of the construction of the mechanism shown in the accompanying drawings, the mechanism of the 65 machine will be grouped and will be described in their grouped relation; thus, for instance, the mechanism for supporting and rotating an annular tire or tire shoe to receive a winding of material thereon will be 70 described under the general heading of feeding mechanism, and the description of the mechanism for applying to or removing a strip of material from a tire or other object will be described under the general heading 75 of the winding mechanism.

Feeding mechanism.—The supporting means for the feeding mechanism embodies a pair of upright standards 1 and 2 spaced from each other and each provided with 80 bases 3 and with tops or heads 4 arranged in the same horizontal plane. The standards 1 and 2 are preferably provided with webs or lateral walls 5 (see Fig. 2). Mounted in suitable bearings in the bases 3 and heads 4 85 of the two standards 1 and 2 are two pairs of vertically-threaded shafts 6 and 7. All of these shafts 6 and 7 are provided at their lower ends with sprocket-wheels 8 and a sprocket chain 9 extends around and engages 90 the threaded sprocket wheels so that all of the shafts are rotated in unison. One of the shafts 6 is provided at its upper end with a bevel gear 10, into which meshes a bevel gear 11 mounted on a shaft 12 mounted in a suitable bearing 13 positioned near the upper end of the standard 1, and on the shaft 12 is a hand wheel 14 by which the rotation of the shafts 6 and 7 is effected. Positioned between the standards 1 and 2 is a vertically-shiftable carriage 15 provided with laterally-projecting lugs 16 interiorly threaded to receive the shafts 6 and 7 whereby the vertical shifting movement of the carriage is accomplished. At the sides of the carriage 105 15 are two pairs of bearings 17. Extending between the members of each pair are cross shafts 18 on each of which is mounted a grooved roller 19. These rollers are spaced apart from each other a suitable 110

distance so as to form a supporting means for an annular object such as a tire 20. The shafts 18 are provided outside of the bearings 17 with sprocket-wheels 85 over which 5 runs a sprocket-chain 86 communicating motion from one roller 19 to the other.

The rollers 19 are caused to rotate and thereby revolve a tire mounted thereon by the following mechanism: Mounted on one 10 of the shafts 18, preferably the left one in Fig. 2 and the front one in Fig. 1, is a bevel gear 21 arranged to mesh with a bevel-pinion 22 splined on a vertical shaft 23 mounted in suitable bearings in the base 3 15 and head 4 of the standard 2. The carriage 15 is provided with a laterally-projecting apertured lug 24 which receives the shaft 23 and which serves to support the beveled pinion 22 and to cause its vertical 20 reciprocation or shifting movement in unison with the carriage 15. The shaft 23 bears nears its upper end a worm wheel 25. Mounted in suitable bearings, formed for instance by apertures extending horizontally 25 through ribs 26 and 27 formed on the side of the standard 2 is a horizontal shaft 28 bearing a worm 29 which meshes with the worm wheel 25. The outer or right hand end of the shaft 28 in Fig. 2 is supported by a 30 bracket 30. On the shaft 28 is a pulley 31 which forms the driving member of a clutch, a driven member 32 is splined on the shaft 28 and is adapted to engage therewith when shifted through the medium of a lever 33 35 fulcrumed at 34 on the bracket 30 and operated by a pull rod 35 the handle of which is positioned within ready access of the operator when standing at the left of the machine in Fig. 2.

40 It will be noted that when the vertical position of the carriage 15 has been secured, the member 32 of the clutch is shifted into clutching relation with the pulley 31 and a motion is communicated to the latter 45 through the medium of any instrumentality such for instance as a belt, the rollers 19 will be rotated in unison in the same direction and consequently revolve a core 20 mounted thereon. Mounted on the upper 50 faces of the heads 4 of the standards 1 and 2 is an inverted U-shaped frame provided with two downwardly-extending legs 36 and 37 resting on the heads 4 and secured thereto by any suitable mechanism. In order to 55 sustain the upper portion of a tire or other annular object mounted on the rollers 19 during the revolution thereof, guiding mechanism which is shown in detail in Fig. 7, is provided. This mechanism consists of a 60 horizontal threaded shaft 38 bearing a hand wheel 39 by which it is revolved and is supported in a threaded bearing 40 so that as the shaft 38 is rotated it is shifted horizontally. Secured to the inner end of the shaft 38 is a yoke 41 bearing a guiding roller 42

preferably inclined at an angle with respect to the U-shaped frame. Fixedly secured to the inner portion of the shaft 38 is an immovable arm 43 to the upper end of which is pivotally connected a link 44. Positioned 70 on the opposite side of the opening inclosed by the U-shaped frame is a bearing 45 in which is shiftably mounted a member 46 arranged in horizontal alignment with the shaft 38 and bearing at its inner end a yoke 75 47 on which is an inclined roller 48. Pivotally mounted at 49 on the rear face of the U-shaped frame is a rocking lever 50 the ends of which are connected with the link 44 and the outer end of the member 46 so 80 that as the shaft 38 is horizontally shifted a corresponding reverse movement of the rollers 42 and 48 is effected, whereby the two rollers are brought toward each other to serve as a guide and support for the upper 85 portion of the tire 20 during its revolution on the rollers 19 and by this means the distance between the rollers 42 and 48 may be changed to accommodate tires of different 90 sizes.

95 *Winding mechanism.*—Briefly, the winding mechanism embodies a pair of broken annuli revolving on offset axes of revolution and constituting a shuttle or a bobbin-carrier. In detail, there is provided on the front face of the U-shaped frame in Fig. 1, a plurality of flanged rollers 51 arranged at the angles of an imaginary hexagon so that an annulus may be revolved on their peripheries. Also secured on the front face of the U-shaped frame is a second series of rollers 52 arranged eccentrically with respect to the series of rollers 51. Mounted on the peripheries of the rollers 51 is a broken annulus 53 provided near the broken portion 105 with counterweights 54 and also provided with a series of apertures in which are mounted wrist-pins 55. The front face of the annulus 53 is also provided with a plurality of horizontally-projecting pins 84 for 110 a purpose to be later described.

115 The axis of the annulus 53 is at 57. Revolvably mounted on the peripheries of the rollers 52 is a second annulus 58 the axis of which is at 59. This annulus is also provided with a plurality of apertures in which are mounted wrist-pins 60 and connecting the wrist-pins 55 in the annulus 53 with the adjacent wrist-pins 60 in the annulus 58 are 120 links 61 for a purpose to be later described. The two annuli are adapted to constitute a shuttle and are arranged to revolve in unison in the same direction during both the winding and the unwinding operations and the revolution of these annuli is effected by the 125 following mechanism:

130 In a suitable bearing extending through the U-shaped frame 36 is a shaft 62 bearing near its rear end a sprocket wheel 63 which receives a sprocket chain 64 running over a

sprocket wheel 65 fixedly secured on the shaft 28. The shaft 62 also bears near its front end a pulley 66. On the opposite leg 37 of the U-shaped frame is rotatably mounted an idler pulley 67. Also mounted on the front face of the frame are a series of hexagonally-positioned idler pulleys 68. A belt 69 extends around the pulley 66 and from thence over the outer face of the annulus 53 to the idler pulley 67 and from thence over the peripheries of the rollers 68 to the pulley 66 so that as motion is communicated from the driving shaft 28 to the shaft 62 the annulus 53 will be revolved. A belt-stretcher 70 is employed for maintaining tension on the belt 69 but as this belt-stretcher may be of any ordinary construction a detailed description thereof is believed to be unnecessary. The counterweights 54 are positioned on the annulus 52 to counterbalance the bobbin and its carrier, a detailed description of which follows:

Bobbin and carrier.—The mechanism, by which a strip of material is wound onto and unwound from a tire or other object, embodies a bobbin-carrier and a bobbin so arranged that the bobbin is permitted to rotate on its own axis, protected by a tension device, during the placement of a strip of material and arranged to be held against independent rotation on its own axis during the unwinding of a strip of material from an object.

In detail, the annulus 53 opposite to the broken portion is provided with a transverse opening constituting a bearing in which is mounted a shaft 71 formed integral with a crank 72 positioned rearwardly of the annulus 53 and between it and the annulus 58. The latter annulus is also provided with an opening to receive a wrist-pin 73 on the opposite end of the crank 72 so that as the annuli revolve in unison the position of the crank arm 72 will always be vertical and this is also true of the links 61 which connect the wrist-pins 55 and 60. By this arrangement any object such as a bobbin secured on the shaft 71 and held against independent rotation thereon would always normally maintain its relative position during its orbital movement about the tire 20. The shaft 71 in front of the annulus 53 is provided with a hub 74 from which projects a boss 75 provided with a laterally extending arm 76. The portion 82 of the shaft 71 which projects forwardly from the boss 74 bears a rotatable drum 77 around which is a band-brake 78 one end of which is anchored at 79, (see Figs. 1 and 6) to the arm 76 and the opposite end of the band is secured to a threaded shaft 80 extending through a suitable aperture in the arm 76 to receive a thumb nut 80' by which the band-brake 78 is contracted for tensioning or entirely preventing the revolution of the bob-

bin-carrier 77. On the front face of the bobbin-carrier are a pair of pins 81 adapted to be received in suitably-formed apertures in the rear face of the bobbin 82' for detachably connecting the bobbin 82' to the bobbin-carrier and inducing or preventing rotation of one with respect to the other. The bobbin is held on the portion 82 of the shaft 71 through the medium of a nut 83 held in position by a bayonet joint, or any other preferable or approved means so that the bobbin may be readily placed on the shaft 82 and removed therefrom.

The placement of a strip of material on an object such as a tire is illustrated in detail in Fig. 3, and in this instance the strip of material is secured to the right side of the tire in this figure and the shuttle embodying the two annuli is revolved in the direction of the arrow and a suitable degree of tension is imposed on the bobbin carrier through the medium of the band-brake 78 to place the required amount of tension on the strip during its placement. During the orbital movement of the bobbin 82' about the tire 20 the latter, of course, is revolved on its own axis through the mechanism already described and the revolution of the bobbin about the tire is maintained until a sufficient supply has been placed on the tire.

It will be noted that as the bobbin-carrier is connected through the medium of the crank 72 with the annulus 58 the vertical or relative position of the crank will be maintained at all times.

If it is desired to unwind a previously placed strip from the tire the band-brake is tightened sufficiently to prevent independent rotation of the bobbin and its carrier and the shuttle is revolved in the same direction as it is during the placement of a strip, but the strip is taken from the opposite side of the tire, or to be more exact, the tire is reversed in position and as the bobbin orbitally revolves about the tire in the direction of the arrow, the strip of material is wound up on the bobbin, see Fig. 4. When it is desired to impose an additional tension upon the strip during its placements, the strip is carried around one or more of the pins 84 on the annulus 53.

From the foregoing it will be seen that the shuttle is rotated in the same direction both for the placement of a strip of material and its removal from an object and that it is not necessary to reverse the revolution of the shuttle for the two operations, the only requirement being that the position of the tire or other object be reversed during the unwinding of a strip of material therefrom.

I claim:

1. A machine for wrapping and unwrapping strips of material from an object comprising a revoluble shuttle consisting of a

- pair of broken annuli loosely united together and revolving on different axes of revolution in unison in the same direction, one of said annuli provided with an opening constituting a bearing, a shaft mounted in said bearing, a crank arm, a wrist pin mounted in a suitable bearing in the other annulus and connected with the free end of said crank arm, a loosely-mounted drum on said shaft, 10 a bobbin loosely mounted on said shaft, a brake applicable to said drum for controlling its rotation, and means for detachably holding said bobbin and drum in interlocked relation.
- 15 2. A machine for wrapping and unwrapping a strip of material from an object comprising a revoluble shuttle consisting of a pair of broken annuli loosely united together and revolving on eccentric axes of revolution in unison in the same direction, one of said annuli provided with an opening constituting a bearing, a shaft mounted in said bearing, a crank arm on said shaft
- the opposite end of which is pivotally connected to the other annulus, whereby when 25 said shuttle is revolved the relative position of said crank arm is always the same, a drum loosely mounted on said shaft, the outer surface of which constitutes a braking surface, a band-brake engaging said 30 braking surface for controlling the independent revolution of said drum, a bobbin on said shaft, interengaging means carried by said drum and bobbin to cause the bobbin to rotate in unison with said drum, 35 means for detachably holding said bobbin on said shaft, and means for rotating said annuli.

In testimony whereof I have hereunto set my hand in presence of two subscribing 40 witnesses.

CURT KUENTZEL.
